TROUSER HANGER

Robert L. Gielow, 320 Indian Trail,
Marietta, Ga. 30060

Filed May 19, 1971, Ser. No. 145,119

Term of patent 14 years

Int. Cl. D6—08

U.S. Cl. D6—252

FIG. 1

FIG. 2

FIG. 3

FIG. 4

FIG. 5

FIG. 1 is a perspective view of the trouser hanger embodying my new design;

FIG. 2 is a top plan view thereof;

FIG. 3 is a side elevational view thereof;

FIG. 4 is a bottom plan view thereof; and,

FIG. 5 is a front elevational view thereof.

I claim:

The ornamental design for a trouser hanger, and the like, as shown.
